UNITED STATES PATENT OFFICE.

ELMER L. LANG AND GEORGE H. LANG, OF BOSTON, MASSACHUSETTS.

MARKING MACHINE.

Original application filed October 9, 1922, Serial No. 593,416. Divided and this application filed January 15, 1927. Serial No. 161,317.

This application is a division of our application Serial No. 593,416, filed October 9, 1922, now Patent No. 1,615,017.

This invention relates to marking machines 5 of the type comprising a platen or work support and a printing head movable toward and from the platen to make the printed impression.

The principal feature of the invention relates to novel means for supporting the platen. According to this feature the platen is yieldingly supported by a spring and is at all times free to be moved downward against the action of the spring, a locking 15 device being provided which normally prevents the platen from moving upwardly but which is rendered inoperative during the making of the printed impression.

In the drawings wherein we have illustrated a selected embodiment of the invention Fig. 1 is a side view of a marking machine embodying our invention;

Fig. 2 is a partial front view.

The marking machine herein shown is of that general type comprising a stand or frame 1 having a head 2 in which reciprocates a vertically-moving plunger 3 carrying a printing head 4 which is movable toward and from a work support or platen 5 on which the work 30 to be marked is supported.

The printing head may carry adjustable type disks having printing characters 6 thereon and these are shown as being inked through the medium of an inking roller 7 carried by a swinging arm 8 and which vibrates between an ink-supplying roll 9 and the type characters 6 all as usual in devices of this character.

The platen 5 is yieldingly sustained so 40 that it will move downwardly when pressure is applied thereto. A locking device is provided for the platen which will at all times permit it to be moved downwardly freely but which will lock it from upward movement except during the time that the printed impression is being made. The platen is carried by a plunger 10 which is slidably through a guiding opening 11 formed in a supporting bracket 12. The lower end of the plunger 50 is pivotally connected at 13 to a lever 14, which is pivoted intermediate its ends to the frame as shown at 15, the end of the lever being acted upon by a pulling spring 16 which tends normally to raise the plunger and thus 55 the platen. Any downward movement of the

platen, therefore, is in opposition to the action of the spring 16.

As stated above a locking device is provided which prevents the platen from moving upwardly except at the time that the printed impression is made but which permits it at all times to be moved downwardly freely. This locking device might be called a one-way locking device because it functions to restrain movement of the platen in one direction only, the platen being at all times free to be moved downwardly but being restrained by the lock in an upward direction only. The plunger 10 is shown as having a ratchet 17 secured thereto with which operates a spring-pressed locking pawl 18 that is slidably mounted in a lateral extension 19 of the bracket 12, said pawl being guided by means of a pin 20 extending laterally from the pawl and which operates in a slot 21 formed in the extension 19. The pawl is shown as acted upon by springs 22 which urge it forwardly into engagement with the ratchet 17.

The pawl and ratchet are constructed, as 80 will be seen from Fig. 2, so that the platen can be moved freely downwardly and during such downward movement the pawl merely clicks over the teeth of the ratchet. The pawl, however, will normally lock the ratchet and 85 consequently the platen from upward movement.

Means are provided, however, whereby this locking pawl is released from the ratchet during the time that the printing impression 90 is being made and so that at such time the platen may be moved upwardly by the action of the spring to bring the work into engagement with the printing head. For this purpose a rock shaft 23 is shown which is journaled in suitable bearings 24 carried by the frame and which has at one end an upstanding arm 25 that is adapted to engage the pin 20 of the pawl. When the shaft is rocked anti-clockwise Fig. 2 the upstanding arm 25 will engage the pin 20 and thus withdraw the pawl 18 from locking engagement with the ratchet. This frees the platen so that it may be moved upwardly by the spring 16.

Means are provided whereby this releasing of the locking pawl is accomplished only at the time that the printing head is in its lowered or printing position and hence when each printed impression is being made the platen is released and is thus moved upwardly 105 110

by the spring as far as permitted by the printing head.

The rock shaft is shown as having another arm 27 fast thereto to which is pivotally connected a link 28. This link is depressed periodically and at the time the printing impression is being made by means of a cam 29 which is fast on a shaft 30 that rotates in timed relation with the movement of the head 4, said cam engaging a cam roll 31 which is carried by a link. The upper end of the link is shown as having a slot 32 therethrough through which the shaft 30 extends, this slot thus serving to guide the upper end of the link and hold it from lateral movement. The roll 31 is maintained in engagement with the cam 29 by means of a pulling spring 33 which is connected at one end to the link 28 and at the other end to the frame 1. The cam 29 makes one rotation for each complete excursion of the printing head 1 and it is so timed and arranged that the high point thereof is in engagement with the roll 31 at the time that the printing head is in its lowered position.

It will be observed that the engagement of the high point of the cam with the roll 31 will depress the link 28 and thereby rock the shaft 23 to withdraw the pawl 18 from its locking engagement with the ratchet thus unlocking the platen and such unlocking occurs just as the printing head reaches its lowered or printing position.

In using the device it is possible to place a stack or pile of pieces to be marked on the platen which may be depressed into its lowered position before the machine is started if desired, or may be left in elevated position. If the platen has been depressed then when the machine is started and the printing head 40 is brought into its lowered position the lock will be released and the spring 16 will force the platen upwardly until the upper piece of the stack meets the type characters on the printing head thus causing a printed impression to be made. As the printing head moves upwardly after making the printed impression the latch 18 will automatically engage the ratchet and thus lock the platen in its lowered position. The operator will then remove the marked article leaving an unmarked article on the top of the pile and during the next printing operation the platen will be again unlocked so as to ensure a proper engagement of the top article of the stack with the printing characters of the printing head.

If, on the other hand, the platen is left in its elevated position when the pile or stack of pieces to be marked is placed thereon then the marking head during its first downward movement will engage the top piece of the stack and will force the platen downwardly

to a position determined by the lowest point to which the marking head is carried, the top piece of the pile being marked during this downward movement. This downward movement of the platen is freely permitted because of the character of the locking device but as soon as the printing head starts to move upwardly the lock will function to retain the printing head in its lowered position.

We claim:

1. In a marking machine, the combination with a yieldingly-supported platen to receive the work, of a one-way lock for the platen which permits the platen at all times to be depressed to the full extent of its downward movement but which normally restrains the platen from upward movement, a printing head movable toward and from the platen, and means to render the lock inoperative during the making of the printed impression.

2. In a marking machine, the combination with a spring-sustained platen to support the work, said platen being at all times free to be depressed against the action of the spring to the lowest limit of its movement, of a pawl and ratchet device to restrain the platen from upward movement, a printing head movable toward and from the platen, and means to render the pawl and ratchet device inoperative while the printing head is making the printed impression.

3. In a marking machine, the combination with a spring-supported platen, to receive the work, of a ratchet rigid with the platen, a spring-pressed pawl engaging the ratchet and co-operating therewith to prevent upward movement of the platen, said platen being free at all times to be moved downwardly against the action of the spring to the lower limit of its movement, a printing head movable toward and from the platen, and means to release the pawl from operative engagement with the ratchet when the printing head is in its printing position.

4. In a marking machine, the combination with a vertically-movable printing head, of a spring-supported platen to receive the work, a ratchet rigid with the platen, a spring-pressed pawl co-operating with the ratchet to restrain the platen from upward movement, said platen being at all times free to be moved downwardly to the lower limit of its movement, a rock shaft having an arm co-operating with said pawl to release the latter, a link connected to said rock shaft and a cam for actuating the link thereby to release the pawl when the printing head is making a printed impression.

In testimony whereof we have signed our names to this specification.

ELMER L. LANG.
